UNITED STATES PATENT OFFICE

GEORGE C. EMRICH, OF COLUMBUS, OHIO

MEANS FOR SUPPORTING HOT AIR RINGS IN FURNACES OR STOVES

Application filed September 28, 1928. Serial No. 309,034.

This invention relates more particularly to coal burning furnaces or stoves in which the upper end of the fire pot is provided with an inwardly projecting hollow ring made in sections and provided with openings for the flow of heated air over the top of the burning fuel for the purpose of promoting the combustion of the fuel and for the better consumption of the smoke. In such devices it has been common to provide an air duct leading to the ring, said duct having one of its sides formed by the fire pot so that external fresh air admitted to the duct through an opening controlled by an adjustable door is preliminarily heated before its entry into the ring.

Because in some varieties of stove or furnace such air supplying rings project considerably into the fire pot they are greatly subjected to the disintegrating action of the air, fire and heat and sometimes are so far destroyed by such action or by the impact of large lumps of coal dumped into the fire pot as to require renewal. Such rings have heretofore been secured in place by bolts or screws, but the destructive action of fire and so forth renders such screws and the ring difficult to remove.

The object of the present invention, therefore, is to provide improved means whereby such rings, or the sections thereof, can be easily placed and replaced without the use of screws or bolts.

The invention is embodied in the example herein shown and described, the features of novelty being finally claimed.

In the accompanying drawings—

Figure 1 is a vertical section, with some details omitted, on the line I—I Fig. 2, of a fraction of a furnace containing the invention.

Fig. 2 is a top plan view of the fire pot with the device removed.

Fig. 3 is a sectional detail, on an enlarged scale, of one of the devices or eyelets for supporting a ring.

Fig. 4 is a detail in plan view of one of the air ring sustaining eyelets, it being shown as seated in a fraction of the top of the fire pot.

50 In the views 5 designates the fire pot which

is shown as made of two parts, the lower part resting on the ash pit or chamber 6. The top of the ash pit has a forward extension 7 that, in connection with horizontal wall 8 and vertical wall 9 and the fire pot, forms an air heating chamber leading to the air distributing ring 10, said ring being coupled to said air heating chamber at its top as best seen in Fig. 2. The ring 10, as before indicated, is best made up of separable sections coupled by the insertion of one into the next. These sections, as well as the top of the air heating chamber are provided with openings 11 permitting the passage of heated air into the combustion chamber.

The upper edge of the upper section of the fire pot is provided with a channel 12 that, at its inner wall is notched as at 13, and socketed as at 14 in the bottom of the channel adjacent the notch. In said notch and socket is seated the shank 15 of an eyelet 15^a, said eyelet having its opening elongated and the shank thereof having an upward projection 15^b, the upper edge of the last preferably coinciding with the rim forming the inner wall of the channel 12.

The inner side of such ring section near each of its ends is formed with a teat 10^a that can be inserted in the appropriate eyelet so that the ring sections are thereby hung in their proper position. The elongation of the opening of the eyelet permits sufficient movement of the ring sections upon each other at their joined ends in the direction of their length, and the lifting of two of the sections at such a joint to allow the teats of the two nearest such joints to be removed from their eyelets and conversely by placing the ends of two sections together in disaligned relation after the other teats have been inserted the teats of contiguous ends can be dropped concurrently into their eyelets. The particular manipulation just described of placing the ring sections is only necessary in inserting the final section. When the ring is so assembled the sections are held from accidental movement downward and from sufficient movement in a circular direction to form a gap between any two of the rings. The dome 17 as shown is provided at its lower

edge with a tongue 17^a, that enters the channel 12, and inner and outer projections or flanges 17^b and 17^c respectively that rest on the upper edges of the walls forming the channel 12 so as to make a tight tongue and groove joint.

In erecting the furnace the ring is first assembled as seen in Fig. 2. The dome 17 is then applied, the channel being first provided with the usual cement for making a tight joint. The application of the dome 17 to the fire pot while, of course, aiding in fixing the eyes, does not preclude the removal or replacement of ring sections at any time that may be desirable without removing the dome. It will thus be observed that the air-ring sections are hung on eyelets that project from the joint between the dome, said eyelets not being subject to the accumulation of ash to interfere with the hanging of the air-ring sections.

The character 18 designates the feed door for the fire pot; 19 a vessel for containing water; 20 a shaker for the grate; 21 the main door for the ash pit and 22 a draft regulating door on the main door of the ash pit.

Holes 23 admit air from the ash pit to the air heating chamber supplying the rings when the ash pit doors, or either of them, is open. After the fire is sufficiently started the supply of heated air to the ring is controlled by an adjustable door 24.

The forms of the parts can be changed without departing from the gist of the invention as claimed.

What I claim is:

1. In a stove or furnace having a fire pot and a separable dome therefor, a tongue and groove connection between said fire pot and dome, a plurality of hanger members each consisting of a shank portion and a portion having a horizontally elongated eye portion, the shank portions of said hanger members secured in said tongue and groove connection, and said eye portion extended into the fire pot chamber, and a plurality of removable air supplying ring members for the fire pot provided with pins engaging said elongated eyes.

2. In a stove or furnace having a fire pot and a separable dome therefor, a tongue and groove connection between said fire pot and dome, a plurality of hanger members each consisting of a shank portion and a portion having a horizontally elongated eye portion, the shank portions of said hanger members secured in said tongue and groove connection, and said eye portion extended into the fire pot chamber, and a plurality of removable air supplying ring members for the fire pot, said ring members having telescoping ends and provided with pins engaging said elongated eyes.

3. In a stove or furnace having a fire pot and a separable dome therefor, a tongue and

groove connection between said fire pot and dome, a hanger member consisting of a shank portion and an eyelet portion, said shank portion secured in said tongue and groove connection, and said eyelet portion extended into the fire pot chamber.

GEORGE C. EMRICH.
